UNITED STATES PATENT OFFICE.

ARTHUR HARDT, OF GODESBERG, GERMANY.

PUMP.

Application filed July 13, 1926, Serial No. 122,120, and in Germany July 23, 1925.

With pumps used in connection with hydraulic gearings for motor cars, lifting devices, hydraulic presses, and the like, the delivery pressure increases with the increase of 5 the resistance. In order to be in the position to overcome that increasing delivery pressure with the motor driving the pump it has become customary to decrease the amount to be delivered in proportion to the 10 increase of the delivery pressure, for instance by varying the eccentricity of an eccentric disk or ring or of a crank or the like so as to accommodate the stroke of the 15 pump piston (or, as regards slide-valve rotary pumps, the path of the slide-valve) to the other condition.

As adjusting manually the amount to be delivered requires at least in certain cases, 20 for instance where hydraulic gearings are employed in connection with motor cars, pretty great attention on the side of the operator, maybe of the driver of the motor-car, it has been endeavored to provide for effecting that adjustment automatically, and 25 it has for this purpose been proposed to make use of an intermittently and automatically acting intermediate member, for instance a piston, so arranged as to be adapted to adjust automatically the amount delivered and to be acted on one side by the 30 delivery pressure and on the other side by an elastic medium.

If compressed air or compressed gas is used as the elastic medium and if the air or 35 gas cushion is so devised that its pressure is always varied approximately proportionally to the length of the path covered by said means independent of its preliminary tension, then the advantage is attained that the 40 product of delivery pressure and amount delivered remains approximately constant at any delivery pressure, so that also the driving motor is loaded approximately constant at all delivery pressures.

45 For the purpose of economically loading the driving motor it is necessary to maintain the initial pressure of the gas or air cushion at a constant high. Therefore according to the invention the air or gas cushion is connected i. e. by means of a non-return-stroke valve with a compressed gas or air source maintaining the initial pressure of the gas or air.

55 The invention is illustrated diagrammatically and by way of example on the accompanying drawing on which a constructional

form of a device designed according to the invention is shown in longitudinal section.

The invention is illustrated diagrammatically and by way of example on the accompanying drawing showing a vertical longitudinal section through a device designed according to this invention.

Referring to the drawing, *a* denotes the rotor of a rotary pump having six pistons 65 1, 2, 3, 4, 5, 6 which rotate together with said rotor and are at the same time reciprocated in the same by the co-operation of rolls *x* attached to the outer ends of the pistons, and of the inner circumferential surface of the annular stator *b*. *c* denotes the stationary slide-valve which is located centrally in said rotor *a*. This latter and the stator or ring *b* are arranged eccentrically with respect to each other, as shown. The eccentricity can be varied (by means herein-after described) by shifting the stator or ring *b*, more or less from the right to the left, or maybe, reversely, this shifting being 70 75 effected automatically.

The arrow 7 in Fig. 1 denotes the direction of rotation of the rotor *a*. The liquid is supplied through the tube *a* into the chamber located above the slide-valve *c* from which it is distributed into the cylinder spaces existing below the pistons just located in the upper half of the rotor, the filled cylinders being emptied by their appertaining pistons when these move through the lower half of their path. The liquid is pressed 80 85 first into the chamber below the slide-valve and then into the delivery pipe *e*.

In the position of the rotor or rotary body *a* and the ring *b* relatively to each other as shown in the drawing the quantity delivered 90 by the six pistons and cylinders, or the six pumps respectively, is the largest because the eccentricity of the ring *b* relatively to the body *a* is the greatest possible. If the ring *b* is shifted to the left, the quantity of liquid 95 delivered will be decreased, and if the ring *b* is shifted so much that its centre and that of the body *a* coincide, the quantity will be diminished to zero. The pressure which the driving motor can overcome with an equal 100 turning moment increases in the same ratio.

The automatic accommodation of the delivery pressure to the pressure resistance is effected by the means of a piston *f* rigidly connected with the ring *b* and being shiftable in the cylinder *g* into which oil can be conducted from the pipe *e* by means of a 110

branch pipe e^1 . The piston f is connected rigidly with a larger piston h which is shiftable in a cylinder i and subjected to the pressure of compressed air.

- 5 Supposing, the ratio between the compressed air present in the cylinder i and the liquid pressure the driving motor can produce at the largest amount of liquid delivered, as well as at the most favorable efficiency, be inverse to the ratio between the sectional area of the piston f and that of the piston h , then in the same moment in which the pressure in the pipe e rises even only quite a little the piston f will be shifted 10 to the left for a corresponding length of way and, consequently, also the piston h will be shifted whereby the pressure of the air present in the cylinder i is also correspondingly increased, the leftward movement continuing until the proportionality mentioned in the preceding lines of this paragraph, viz., between the pressure of the liquid and that of the air, has been re-established. Together with the pistons h and f 15 also the ring b will be shifted to the left, in consequence whereof, firstly, the quantity of liquid delivered by the pumps 1-6 is diminished correspondingly, and secondly, the pressure which the driving motor can 20 overcome at the same turning moment is increased correspondingly.

If the axial length of the cylinder i or, more precisely, of the path of the piston h , corresponds to the greatest eccentricity 25 existing between the ring b and the rotatory body a , then the delivery pressure which the driving motor can overcome at the same turning moment will, theoretically (as the compression of the air takes place nearly 30 isothermically owing to the large cooling surfaces), be accommodated accurately to the variation of the delivery resistance.

If the normal delivery pressure amounts, for instance, to 10 atm., the length of the 35 path of the piston to 20 cm. and the length of the air cushion to 10 cm., and if, furthermore, the delivery pressure rises, owing to an increase of the resistance, to 20 atm., then also the pressure exerted by the liquid piston 40 upon the air cushion enclosed in the chamber i will be doubled, in consequence whereof the volume of the air will be reduced to one half according to Gay-Lussac's law, the piston h will be shifted to the left by 5 45 cm., and the stroke of the piston reduced to one half, so that the product of delivery pressure and amount of liquid delivered will remain unchanged.

If the pressure should rise to 30 atm., then 50 also the pressure to which the air-cushion i is subjected will become the threefold of what it had been initially, and the air will be compressed to one third of its initial volume; as a further consequence the stroke of 55 the pump piston will be reduced to one third

of its initial length, so that the product of delivery pressure and amount delivered remains again constant.

In practice the chamber i will often times be made somewhat longer than corresponds to the change of position of the eccentric ring b from the shortest to the longest stroke of the piston in order to make up for the decrease of the efficiency arising when the amount delivered is only small.

If for any reason, for instance, in consequence of the unavoidable leakiness of the piston, a pressure loss is caused in the chamber i , the motor will not be economically loaded. To obviate this draw-back according to the invention the chamber i is connected by a return-stroke valve m with a compressed gas or air source, for instance a reservoir n maintaining the initial pressure of the gas or air cushion by filling up the eventual gas losses in the chamber i at those times at which only the normal fluid pressure is operative against the air cushion.

The preliminary tension of the air cushion i is preferably made adjustable, for instance, by first regulating the pressure in the chamber n and then adjusting correspondingly the pressure in the chamber i by opening the non-return valve m in the vessel n . This latter may be provided for that purpose with a branch provided with a cock y or any other suitable device permitting either to blow off the pressure more or less or to increase it by means of a pump or a liquid under pressure. Reducing the pressure may become necessary, for instance, if a cylinder or several cylinders of an internal combustion engine driving the pump fail from any reason, for instance by having been damaged, and the service is to be continued with the remaining cylinder or cylinders which cannot, of course, produce the normal pressure and deliver the same amount of liquid than prior to the changed state.

In the constructional form shown by way of example a second hydraulic piston o connected rigidly with the other pistons and located in a cylinder p is provided this cylinder is connected by a branch pipe e^2 with the pipe e^1 , and a three-way cock r is inserted into this connection. If the position of the plug of the cock is that shown in the drawing so that the liquid under pressure can flow from the pipe e^1 not only into the cylinder g , but into the cylinder p ; also, the pressures exerted upon the pistons f and o act together, but if the position of the plug is such that the liquid leaves the cock through the lateral aperture r^1 of the cock casing that additional pressure (on the piston o) does not exist. The object of this additional device is to place the attendant or the driver into the position to avail himself suddenly of an excess of power as required, for instance, at starting a motor-car.

I claim:

1. A pump for hydraulic gearings, lifting devices, hydraulic presses, and the like, comprising, in combination with the respective pump proper, means adapted to regulate the quantity of liquid under pressure delivered by the pump, an adjustable member connected with said first means for the purpose of adjusting it and being actuated in one direction by the pressure produced by the pump, a gas cushion actuating said adjustable member in the opposite direction, having a certain preliminary tension and being adapted to vary its pressure proportional to the length of the path covered by said adjustable member and means adapted to automatically maintain the said preliminary tension.
2. A pump for hydraulic gearings, lifting devices, hydraulic presses, and the like, comprising, in combination with the respective pump proper, means adapted to regulate the quantity of liquid under pressure delivered by the pump, an adjustable member connected with said first means for the purpose of adjusting it and, being actuated in one direction by the pressure produced by the pump, a gas cushion actuating said adjustable member in the opposite direction, having a preliminary tension exerting on said adjustable member a pressure corresponding to the pressure exerted in the opposite direction by the normal delivery pressure, and means adapted to automatically maintain the said preliminary tension.
3. A pump for hydraulic gearings, lifting devices, hydraulic presses, and the like, comprising, in combination with the respective pump proper, means adapted to regulate the quantity of liquid under pressure delivered by the pump, an adjustable member connected with said first means for the purpose of adjusting it and being actuated in one direction by the pressure produced by the pump, a gas cushion actuating said adjustable member in the opposite direction, having a certain preliminary tension and being adapted to vary its pressure proportional to the length of the path covered by said adjustable member and an additional means adapted to increase the action of the liquid pressure upon said adjustable means for the purpose set forth.
4. A pump for hydraulic gearings, lifting devices, hydraulic presses, and the like, comprising, in combination with the respective pump proper, means adapted to regulate the quantity of liquid under pressure delivered by the pump, an adjustable member connected with said first means for the purpose of adjusting it and being actuated in one direction by the pressure produced by the pump, a gas cushion actuating said adjustable member in the opposite direction, having a preliminary tension exerting on said adjustable member a pressure corresponding to the pressure exerted in the opposite direction by the normal delivery pressure, means adapted to automatically maintain the said preliminary tension and means for adjusting said preliminary tension.

In testimony whereof I have affixed my signature.

ARTHUR HARDT.
